(57) **CLAIM**

The ornamental design for a frame cover, as shown and described.

DESCRIPTION

FIG. 1 is a perspective view of a frame cover for a medical bed embodying my design.

FIG. 2 is a right side elevational view thereof.

FIG. 3 is a left side elevational view thereof.

FIG. 4 is a top plan view thereof.

FIG. 5 is a bottom plan view thereof.

FIG. 6 is a front elevational view thereof; and,

FIG. 7 is a rear elevational view thereof.

The broken line shown throughout the drawing figures forms no part of the claimed design.
